ABSTRACT

Ladder extension means for fighting fires comprising a portable support positionable in a window or other wall opening. The support is provided with means for fixedly bracing it against movement, and means at its outer end to receive a ladder. The means for receiving the ladder is movable so that the ladder may be positioned in selected altitudes with respect to the building providing extension from the wall opening to another part of the building, such as from floor to floor.

FIRE LADDER EXTENSION APPARATUS

BACKGROUND OF INVENTION

The present invention relates to fire fighting apparatus and particularly to apparatus for extending ladders and the like from floor to floor of high-rise buildings.

While fire fighting equipment is generally very advanced and sophisticated, a particular problem is found in fighting fires in high-rise buildings, that is buildings over nine stories or approximately 100 feet in height. At the present time there are many buildings of this size, and even greater, in every city in the world and more are being built every day. Such buildings have a brick, aluminum, or other material facade, and are characterized by an excessive rectangular array of windows and steel and concrete floors, walls and passages. The windows are usually closed and non-openable to provide a hermetic seal for the heating and air-conditioning systems. Consequently, the individual floors although apparently "fire proof" constitute a highly inaccessible and virtually impregnable container for any fire which may occur in the furnishings, walls etc., thereof and for victims caught therein. It has been the experience of fire fighters that any fire in a modern high-rise building results in the creation of a trap and that at present the most effective manner of fighting such fires has merely been to contain it to one or two floors until it has run its course. As a result considerable damage and possibly great loss of life occur before the fire can be extinguished.

This problem is most serious when the fire occurs on the upper stories of such building since the excessive smoke and heat generated prevents access to the floor on which the fire occurs, from within the building, and the excessive height prevents stringing of ladders on the exterior of the building to gain access to that floor from without. At present, any point or floor above nine stories or above approximately 100 feet cannot be reached from outside the building with ground bound ladders nor is there any effective means for reaching such levels from outside the building.

It is the object of the present invention to provide a system and apparatus for carrying it out which provides the fireman with ability to gain access to the upper stories of high-rise buildings for himself and for the necessary equipment to fight the fire.

It is another object to provide ladder extension means for gaining access to the upper floors of the high-rise buildings.

It is still another object of the present invention to provide a ladder extension by which a ladder may be strung between the upper floors of a high-rise building and which may be easily used for equipment and personnel.

It is another object of the present invention to provide ladder extension means by which a fire in the upper stories of a high-rise building can be reached, remotely, from a lower floor and which may be adapted to contain fire equipment which may be remotely operated to ventilate the upper building and to supply a stream of water from outside the building while also providing a portable fire escape for the occupants to seek refuge in the floor below.

These objects and advantages as well as the advantages arising out of the specific details of the present

invention are set forth in the following disclosure of the preferred embodiments of the invention.

SUMMARY OF THE INVENTION

According to the present invention fire fighting apparatus is provided comprising a portable support which may be positionable in a wall opening such as a window or a hole created for this purpose. The support is provided with means to brace it against axial movement in the opening and to anchor its inner end to the floor of the building. Extension means is mounted at the outer end of the support which is adapted to receive and hold a ladder at an angle to the support. The extension means is movable so that the ladder may be selectively tilted and positioned along the side of the building.

Preferably, the extension is movable freely in one direction and incrementally supported in the other, so that the ladder mounted in it could be made to move with some degree of force against the building to strike and break remote windows, or similar panel structures.

The extension means is preferably mounted on a rotatable table which may be swung full circle in a horizontal plane so that the ladder seated on it could be made to similarly rotate. As a result of this ability and the ability to tilt the ladder, the ladder may be positioned so that its tip can cover a wide area or expanse of the building facade.

The present apparatus has the advantage that fires at high and remote floors can be fought without firemen going directly to that floor from the building interior using elevators and stairs that are often unusable because of smoke and heat. That the building may be pierced and water and other equipment delivered from a remote position even though the fire is so high up that conventional equipment would not be able to reach it.

Further in accordance with the present invention, means are mounted at the end of the ladder to facilitate the breaking of glass window panels or similar building panels so that access to the building remote from the support can be obtained. The breaker means may be mounted directly on the end of the ladder or it may be mounted on a water nozzle or hose pipe secured to the end of the ladder. This enables the floor wherein the fire rages to be ventilated and possibly soaked with water before the firemen scale the ladder. As a result injury to firemen can be substantially reduced.

Full details of the present invention are set forth in the following description and depicted in the accompanying drawings.

BRIEF DESCRIPTION OF THE DRAWINGS

In the drawings,

FIG. 1 is a perspective view of the apparatus of the present invention placed in use in a window of a high-rise building,

FIG. 2 is a side elevation view of the apparatus of FIG. 1, in partial section,

FIG. 3 is a partial perspective view showing in detail the bracing member,

FIG. 4 is an enlarged detailed view of the ladder extension and supporting tormentor,

FIG. 5 is a section along line 5-5 of FIG. 4,

FIG. 6 is an enlarged detailed view similar to FIG. 4, partially sectioned showing the ladder stop or keeper means,

FIG. 7 is a plan view in the direction of line 7 of FIG. 7,

FIG. 8 is a front elevation view of a building and its apparatus of the present invention in use,

FIG. 9 is a plan view of the showing of FIG. 8,

FIGS. 10, 11 and 12 are side elevational views showing the sequence of operation of the apparatus,

FIG. 13 is an enlarged view of a second form of glass breaker assembly, and

FIG. 14 is an enlarged sectional view of the device of FIG. 13.

DESCRIPTION OF THE INVENTION

The details of the present invention may be more easily understood by reference first to FIG. 1 wherein it is shown completely installed and in use combating a fire in a high-rise building generally depicted by the numeral 10. Schematically the building comprises a plurality of generally horizontal floors 12, enclosed in a facade having windows 14 (in which the apparatus is shown to be located) framed by vertical mullions 16 and horizontal lintels or sills 18. For the sake of exposition it is to be assumed that a fire, indicated by smoke 20, is in progress at the top most floors 22, to which access by normal means is not possible.

The apparatus of the present invention comprises an elongated supporting truss 24 having a horizontal deck 26, made of steel mesh, rubber or similar material in an easy tracking surface. In general the truss may be of any length, although a suitable length for convenient use will be about 6 - 10 feet. Depending from the deck are rectangular side frames 28 which have a horizontal top rail 30 extending above the deck and a horizontal bottom rail 32 spaced below the deck, adapted to rest on the window sill 18. At the rear end or the end normally to be positioned within the building, the truss is provided with a pair of braces 34 (FIGS. 2 and 3) each comprising a screw jack 36 pivotally connected at one end to bottom rail 32 and fixed at the other end to a fastening plate 38 having holes 40 through which suitable bolts, spikes or other means may be driven to secure the plate 38 to the floor of the building. The jack 36 has an adjustment handle by which the screw can be extended or retracted to place the deck 26 on a horizontal plane. The front or the forward end of the truss 24 is provided with a pair of parallel bracing arms 42 which curve backwardly at an angle with respect to the deck and below it. The bracing arms 42 are integrally secured, as by welding, to a rectangular channel member 44 which is disposed transverse to the longitudinal axis of the truss. Movable extending from each end of the channel member 44 is a supporting rod 46 which may be adjusted so that both rods 46 span the distance between at least two of the building's mullions 16, or in their absence to span a sufficiently wide section of the building to give support to the truss.

Mounted to be adjustable along the bottom rail 32 is an inside support brace 48 (FIG. 3). The inside brace 48 comprises a transverse bar 50 in the center of which an abutment block 52 is fastened to the rails 32 by a wing nut and screw 54 extending through a slot 56. The block 52 and the transverse bar 50 are thus movable along the axis of the truss toward and away from the inside wall of the building. It may be preferred to provide hooked grippers 58, secured by a thumb screw 60 at each of the ends of the transverse brace bar 50 to further enhance securement against the inside wall partic-

ularly when such walls are uneven or when heating or air conditioning equipment or the like are located directly in front of the window.

Vertical brace poles 62 (FIGS. 1 and 2) in the form of a telescoping rod and sleeve, are provided to hold the truss within the window frame itself. Each pole 62 has an open channel piece 64 at its lower end which grasps over the edge of the top rail 30. The rod and sleeve are provided with a series of holes 66 into which a retaining pin 68 may be placed once the pole is extended to its desired length. The upper or outer end of the pole is provided with an adjustable screw jack 70 similar but smaller than the screw jack 36, the end of which has a show 72 which fits abuttingly against the lintel of the window frame.

Located at the forward or exterior end of the truss is a turntable assembly, generally depicted by the numeral 74. As seen in FIG. 2, the turntable assembly comprises a horizontal ring shaped thrust plate 76 which is integral with, and preferably a continuation of, the deck 26. The plate 76 is provided with annular ball bearing race grooves 78 on both its top and bottom surfaces and is sandwiched between a pair of bearing plates 80 and 82 which are integrally connected to each other, for conjoint unitary rotation by a central hub 84 extending through the thrust plate 76. The bearing plates 80 and 82 are provided with race grooves corresponding to the groove 78 in the thrust plate 76 and ball bearing 86 are located therebetween. A shaft 88 extends vertically within the hub 84 and is supported by an arm 90 secured to the truss. The lower bearing plate 80 is provided with a bevel gear 92 about its outer, circumferential edge which meshes with a bevelled pinion 94 mounted at the end of a central shaft 96 which extends axially through the truss 24 beneath the deck 26. At the rear end of shaft 96 is located a crank wheel 98 having a handle by which it may be turned. The circumferential edge of the crank wheel 98 is provided with a plurality of uniformly spaced holes 100 into which a locking pin 102 pivotally mounted on the truss is insertable. Because of the annular race grooves 78 the bearing plates 80 and 82 are thus rotatable about the shaft 88 through 360° clockwise or counterclockwise, merely by rotation of the crank wheel 98 and it is lockable in any desired position by the locking pin 102.

Secured to the upper bearing plate 82 is a turntable surface 104 to the outer edge of which a ladder boot 106 is pivotally mounted by a pair of hinges 108. As seen in FIGS. 4, 5 and 6, boot 106 comprises a pair of thick metal open ended channel members 110, which extend beyond the edge of the turntable surface and which are joined by a cross piece 112, into which a ladder is insertable. The boot 106 is adapted to be releasable placed and held in a number of angular positions with respect to the horizontal turntable surface 104, by a tormentor assembly 114. The tormentor comprises still another screw jack 116 pivotal connected at one end by a fixed journal bracket 118 to the boot cross piece 112 and having a free end constituting a pawl 120 resting on an elongated rack 122 secured face up on the turntable surface 104. The rack 122 comprises a plurality of uniformly spaced teeth comprising risers 124 and treads 126, against the latter of which the pawl 120 of the jack 116 is adapted to abut. The angle of the treads and risers are such that the abutment of the pawl stabilizes the boot in the given angular position, while permitting simple release and adjustment when desired.

Pivottally mounted at the pawl 120 is a pressure release lever 128, held by a cross pin 130. The edge of the release lever 128 is coextensive with the end of the pawl 120 and is also adapted to rest on the tread 126, extending as seen in FIGS. 4 and 5 parallel to the surface of the tread. Thus, by depressing the release lever 128, in the direction of the arrow A, the pawl is caused to be disengaged from the tread and will slide down the riser due to the weight of the boot 106. By maintaining the release lever 128 depressed the pawl may be made to move quickly and easily from one end of the rack 122 to the other. Preferably actuation of the release lever 128 is effected by pressing on it with the foot. The pawl 120 can be made to elevate up over the riser merely by moving the boot 106 counterclockwise, i.e., increasing its angle.

Preferably the rack 122 is sufficiently long to provide for an angular range of boot elevation from 0° to 90°. To prevent the boot 106 from tipping over and falling outward from the truss, the rack 102 is covered by a slotted shroud 132 which is closed at its forwarded end 134 and open at its rear end 136. The shroud 132 covers the extending pin 130, holding the release lever 128, which may be removed from the rear end 136 but which is stopped by the forward end 134. To provide for further and close adjustment of the angle of the boot the jack 116 is provided with an adjustment collar 138.

A ladder bank assembly generally depicted by the numeral 140 is adapted to be removably inserted within the boot 106. The ladder bank 140 comprises (FIG. 1) a bed ladder 142, a fly ladder 144 and at least one extension ladder 146 nested within each other and provided with a fly halyard 148 and securing locks 150. The ladder bank and the individual bed, fly and extension ladders are generally conventional in structure and arrangement and any standard aluminum or wood or combination assemblies may be used, even those employing hand and guard rails and truss rail construction. The bed ladder 142, however, is provided with a stop member 152 extending from outer surfaces of each of its side rails 154 near their upper ends. These stops 152 act to abut against the top edge of the boot 106 and limit the movement of the bed ladder in the boot. Further, the bed ladder is provided with a halyard 156 one end of which may be permanently fixed to the lower rung of the bed ladder or provided with a removable snap-hook 158. Both the fly halyard 148 and the bed halyard 156 are adapted to run over pulley sheaves 160 (FIG. 2) which are mounted on the boot and pass over the deck 26 into the building. It is noted here only briefly that the ladder assembly is placed in the boot in nested condition and pushed outward through the open channels of the boot until its center of gravity shifts beyond the truss 24 and its weight causes the boot to tilt upward. In this manner the ladder assembly may be passed through the window.

Thereafter, the bed halyard is pulled and the entire ladder assembly 140 lifted until the bottom feet 162 (FIG. 6) of the bed ladder rise above the horizontal plane of the turntable. To fix and hold the ladder assembly in this raised condition, a pair of latching keepers 164 are mounted to the turntable surface in line with the channel members 110 of the boot. The keepers 164 are manually shoved beneath the feet 162 of the bed ladder and provide a bottom on which the ladder assembly will rest. Because of the weight the ladder

assembly latches should be secure. However, to insure further that they will not move, the latch may be made with a freely movable bolt held in a slotted housing having fixed angular transverse slots to hold the bolt from axial movement. Preferably, the end of the keeper 164 is provided with a spherical knob 166 to cooperate with the conventional concave foot of the standard bed ladder. After the bed ladder is secured the fly and extension ladders may be opened.

To permit easy access to the ladders once extended, semicircular removable platforms 168 (FIGS. 1 and 7) are secured to the side frames 28 of the truss. On the underside of each platform there is welded a pin 170 which fits into a hole or bearing member 172 formed at the end of the side frame beneath the turntable and an angular bracket 174 in which a bolt 176 extends into a longitudinal slot 178 formed in the side frame and which is held by a wing nut or the like. Fastening of the wing nut holds the platform securely in coplanar with the turntable surface. A third platform member 180 is provided which comprises a rectangular plate having a pair of parallel arms 182 extending from each of the short edges which arm fits within a key way 184 (FIG. 4) formed on the exterior surfaces of the boot channels 110. The keyway 184 is located above the lower end of channels 104 so that the third platform 180 lies in a horizontal plane above the turntable thus not interfering with the ability of the turntable and the boot to rotate about a full 360°, as seen in dotted lines in FIG. 7.

The ladder assembly serves not only to support firemen attempting to reach the site of the fire itself but serves also as an extensible means by which the firemen can perform numerous acts from a remote distance. Thus, as seen in FIG. 1, a ladder pipe 186 is secured to the end wings of the extension ladder, by suitable and conventional quick disconnect clamp 188. A water hose 190 leads from the pipe 186 into the building or to the street where it is connected to a source of water. The pipe 186 may be manually operated or it may be remotely operated by guide ropes, etc., as is well known. To direct the water from the pipe 186 anyone of a number of nozzles 192 may be used. To further aid in the fire fight a window glass breaker assembly 194 is provided which fits over the nozzle and extends forwardly thereof. The breaker assembly comprises a pair of heavy steel rods 196 running parallel to each other and to the axis of the nozzle. The arms are held by a cross member 198 which are provided with ring like snap fittings adapted to be secured on the nozzle, the nozzle being made with cooperating grooves to receive the fittings. The breaker assembly may be secured on the nozzle by other fastening means, such as clamps, bolted and screwed about the nozzle, screw fasteners or the like.

In general, pipe fittings and nozzle supplied for use on extension and fly ladders have several degrees of movement. Firstly, the head of the pipe to which the nozzle is attached may swing about the longitudinal axis of the pipe. Secondly the nozzle may also rotate with respect to the pipe about the longitudinal axis of the nozzle. As a result the tip of the nozzle and the breaker assembly can be made to move in corresponding directions and assume a large if not infinite number of attitudes.

To illustrate the use of the equipment of the present invention, we return to the assumed fire condition at

the top floor of a high rise building. The sequence of operation is depicted in FIGS. 8 through 12, as well as in FIG. 1.

The equipment being easily portable because of its size, weight of materials, and separability of its several parts, such as the truss and ladder in particular, is carried by the fire crew directly to the situs of operation. Generally the equipment will be carried up the elevator, stair shaft, or by pulley and winch along the side of the building to a window position one floor directly below that containing the fire or other target area. A crew of no more than five to six men are necessary. When reaching the selected window, the window is removed. In hermetically sealed buildings windows are not easily removed and a sheet of pressure-sensitive tape (Scotchgaurd No. 898, 3-M Corp) must be placed over the inside of the window, so that the glass may be broken without shattering splinters into the street or on the firemen working below or nearby. The pressure sensitive tape is pierced with a Halligan Hook or the like and the broken glass peeled inwardly into the building. After the window is cleaned of all shards, the truss 24 without the ladder bank, is placed through the window and its bottom rail 32 allowed to rest on the sill. The truss is then drawn back into the building until rods 46 of outside brace member 44 abut against the facade of the building. Thereafter the inside brace member 48 is shifted forwardly to engage the inside wall of the building and its retaining wing nuts 44 locked. The hook like guppies 48 may also be positioned if the wall is uneven or if its additional safety value is required. At the same time the floor brace 34 is positioned, its jack 46 extended and its floor plate 48 fastened to the floor 12. In concrete buildings the fastening may be accomplished by ramsetting a stud rivet or bolt with a hydraulic hammer, or Ramset gun of known type.

The ladder bank 140 is then slid into the boot 106 until its cleat or stop 152 abuts the top end of the boot channels 110. Preferably, the extension ladder 146 is extended and secured with respect to the fly ladder 144 so that the ladder pipe 186 and nozzle 192 may be clamped directly to the extension. It will be noted from FIG. 4 that on insertion of the ladder back into the boot 106 a major portion of ladder extends below the edge of the turntable surface 104. This causes the ladder to pivot the boot and to assume a generally vertical position with a portion of the ladder bank below the turntable surface; the ladder bank being prevented from falling by the stops 152. Thereafter the bed and extension halyards are placed about the sheaves 160 and the bed ladder raised above the level of the turntable surface. As soon as this is done the keepers 164 are latched in place below the feet 162 of the bed ladder and the ladder allowed to rest against the building. On raising the ladder bank, the ratchet and pawl tormentor is allowed to move freely and automatically forward and then backward until the position of the ladder is obtained. The platform members 168 and 180 are then positioned in place as are the vertical bracing poles 62. This can be done by a fireman mounting the truss, as the truss is otherwise firmly placed in the window and on the floor. The brace poles 62 act to prevent rocking or tilting movements of the truss once firmly placed between the lintels and the guard rails.

Thereafter the fire crew is ready to go to work on the fire or target area. The turntable is rotated by manipu-

lation of its crank wheel 98 and the fly ladder 144 extended by pulley on its halyard 148 until the nozzle 192 is positioned opposite and approximately 2 feet away from the object window on the top floor. As seen in FIGS. 1 and 8, because of the flexibility allowed by the 360° rotating table, the swing of the pipe and that of the nozzle, the nozzle may be placed in front of any one of several windows on the top floor, to give access to any one desired. Generally several windows on the top floor will be utilized in the fire fight either to be broken for ventilation or to be broken or removed to gain access to this floor. When the ladder is positioned in front of the desired window the crank wheel is locked by pins 102 and a crew man stands on the deck 26 at the tormentor. The crew man releases the pawl of the tormentor by pressing on the lever 128 allowing the ladder bank to fall against the building and the nozzle to fall against the window. The force of the falling ladder will cause the breaker assembly 194 to break the window. If this is not accomplished on the first try, the man may then reposition the ladder away from the building and repeat the process by again releasing the lever 128. He may also assist the ladder by violently shaking it if he wishes. The pointed breaker assembly 194 is generally sufficient to break most windows without violent effort, however, with some double pane safety glass windows, several tries may be needed, particularly to completely clean the window of all glass. Additional effort can be exerted on the ladder by a fireman using a 6 foot pipe hooked over the ladder rungs. The ladder falling toward the building pushes the glass into the building thus preventing a showering of broken glass into the street or on the truss below. The turntable is repositioned, the ladders are extended or retracted, and the procedure repeated at as many windows as are needed to obtain the desired access or ventilation.

Once the windows are opened, the fireman have numerous working options. A stream of water can be directed through the hose and nozzle into the top floor. Generally a stream of 50 - 60 psi may be used. This should clean out the windows and remove any fire from about the window. The fireman may climb the ladder to the top floor with a hand hose. To do this the ladder is first retracted and the tormentor released so that the ladder leans against the sill of the top floor window. Rescue operations may also be conducted, the firemen leading the victim down the ladder, under conventional procedure. The ladder may be placed at a 72° angle to the wall of the building so that the victim may more easily climb down it. Lastly, the ladder may be used to carry equipment to and from the top floor to fight the fire thereon. It is most likely that during the course of fighting the fire each of these options may be employed.

The number of uses to which the present apparatus may be put are dependent solely upon the ingenuity of the fire crew employing the same. Because of the portability of the equipment the apparatus may be carried to places which are otherwise inaccessible to normal equipment. Because of the rotatability of the turntable and the ladder bank mounted on it, and the ability to direct the nozzle and breaker assembly as desired, the fire fighters, the water stream and other devices may be directed pointedly at the source of the fire, the place where victims may be located, at any desired target area. Above all the present apparatus allows access to floors and areas directly above the fire fighter and at

heights not previously possible. It may also be used to scale buildings spaced away and separate from that in which the fire crew is located.

When operations are complete and the fire extinguished, the auxiliary equipment, hose, pipe, etc., are removed and the platform members taken off. The tormentor is operated to place the ladder in vertical position, the ladder bank closed and the ladders lowered through the boot. The ladder bank is then tilted to rest on the deck and then removed from the boot into the building. The ladder bank is in an assembled and immediately reusable condition. The brace poles and floor braces are removed and the truss withdrawn from the window. The truss assembly also remains in an unitary condition and is immediately reusable. Except for the need to clean the equipment after use, none of the equipment need be rebuilt, repaired, or replaced. This is particularly advantageous, since it is most likely that the equipment may need to be moved during the course of fighting a fire from one floor to another and from one side of the building to another.

In FIGS. 13 and 14, a modified version of breaker assembly is depicted which is mounted directly at the end of the extension ladder 146 and not on the water nozzle. As seen a pair of cylinders 200 are pivotally secured at 201 to the ends 202 of the ladder rails and are held by a cross member 204. The cylinders 200 retain a piston rod 206 loaded by a heavy spring 208. The spring may be connected to a rope 210 which may be manually pulled or wound about a winch to compress the spring 208. On release of the restraining rope or the winch on which the rope may be wound, the spring 208 will force the rod 206 forwardly with a strong window-breaking force in a ram action. The rod 206 may also be actuated by providing a release catch (not shown) against which the rod may be precompressed and held, the catch being released by a pull on a rope connected with such catch, allowing the spring to freely push the rod forwardly. Suitable latches or catch means 212 are provided to hold the cylinders in position perpendicular to the ladder. The hose nozzle 192 may also be mounted to the cross member 204 as shown in FIG. 13.

As will be seen from the foregoing, the present invention provides greatly improved equipment for fighting fires, particularly in high-rise buildings. The disclosure is illustrative and enabling one skilled in the art to reproduce the equipment and use it with no difficulty or experimentation and allowing the user to make any of several modifications and changes. It is not intended that the disclosure be limiting of the invention in any manner.

What is claimed is:

1. Apparatus for fighting fires in high rise buildings comprising a portable support positionable through a wall opening and securable with respect thereto to extend outwardly therefrom, extension means connected with and movable on and relative to said support, a ladder connected with said extension means and to be supported thereby at an angle and for movement relative to said support, whereby said ladder may be extended in length away from and retracted to said support along the outside of the building.

2. The apparatus according to claim 1 wherein said support is elongated having a deck adapted to be supported on a sill of the wall opening above the floor thereof, and a brace extending downwardly from the

rear end of said support including means for anchoring said brace to the floor.

3. The apparatus according to claim 2 wherein said brace includes means adjustable in length whereby said brace may be extended or retracted to adjust said deck relative to the floor.

4. The apparatus according to claim 2 including a table rotatable in a horizontal plane at the forward end of said support, said table supporting said extension means, and means for rotating said table into selected positions.

5. The apparatus according to claim 4, means on said support for remotely adjusting the position of said table.

6. The apparatus according to claim 1 wherein said extension comprises at least a channel member having an open end to receive said ladder, said channel member being pivotably secured to said table and including means for supporting said channel member in selected angular positions with respect to said table.

7. The apparatus according to claim 6 including means on said channel member and selectively movable to engage and retain said ladder in its extended position.

8. The apparatus according to claim 6 wherein said means for supporting said channel member comprises an elongated arm secured at one end to said channel member and resting at its other end on a ratchet member secured to said table having a plurality of fixed stop positions.

9. The apparatus according to claim 8 including means for releasing said arms from said ratchet stop positions to permit release of said extension means.

10. The apparatus according to claim 1 including operable ram means on the end of said ladder, means connected with said ram means to operate the same to break glass when so rammed.

11. The apparatus according to claim 10 including a hose nozzle secured to said ladder, said ram means being mounted on said nozzle.

12. The apparatus according to claim 10 wherein said ram means comprises at least one pointed instrument.

13. Fire fighting apparatus comprising a rotatable base, a ladder boot pivotally mounted along said base and having means for receiving therein a ladder end first, said ladder boot being freely movable in one direction from a first position horizontal to said base to a second position substantially vertical to said base, a tormentor incrementally bracing said boot to allow stepped movement thereof in the opposite direction from said second to said first positions, an extension ladder slideable within said boot, said boot being pivotally displaced from said first to said second position by the weight of said ladder, whereby at least a portion of said ladder depends below said base, means for raising said ladder above said base in said second position and means for fixedly maintaining the ladder so raised.

14. The apparatus according to claim 13 wherein said ladder comprises an assembly of two or more ladders extensible with respect to each other.

15. The apparatus according to claim 14 including means for releasing said tormentor from incremental bracing to cause said ladder to drop from said vertical to horizontal position.

16. The apparatus according to claim 15 including means for limiting the extent of movement of said ladder in said boot.

17. A portable fire apparatus for use in a building comprising releasable means to releasably secure said portable apparatus inside the building with respect to a floor of the building with a portion of said apparatus extending from the interior of the building floor and outward of the building exterior, ladder means on said portable apparatus extending exterior of the building and movable up and down relative to another floor of the building with respect to which the apparatus is secured, and means on said apparatus at the building ex-

terior connected with said ladder means to move the same relative to the exterior of the building.

18. A portable fire apparatus for use in a building as in claim 17, means on said apparatus for supporting a fluid hose exterior of the building for movement up and down and sideways relative to said other floor and relative to the secured apparatus.

19. A portable fire apparatus for use in a building as in claim 18, force applying means on said apparatus to apply a window breaking force from the exterior of the building, and means on said apparatus to operate said force applying means remote therefrom.
